(57) **CLAIM**

The ornamental design for a drinking bottle, as shown and described.

DESCRIPTION

FIG. 1 is a front perspective view of a drinking bottle showing our new design;

FIG. 2 is a rear perspective view thereof;

FIG. 3 is a first side elevational view thereof;

FIG. 4 is a second side elevational view thereof rotated by 180° relative to the first side elevational view of FIG. 3;

FIG. 5 is a top plan view thereof;

FIG. 6 is a bottom plan view thereof;

FIG. 7 is a front elevational view thereof; and,

FIG. 8 is a rear elevational view thereof.

The broken lines in the FIG. 6 drawing are included for the purpose of illustration and form no part of the claimed design.
